Primary Examiner — Mary Ann Calabrese(74) *Attorney, Agent, or Firm* — Absolute Technology Law Group, LLC(57) **CLAIM**

The ornamental design for an associative image display kit, as shown and described.

DESCRIPTION

FIG. 1 is an isometric plan view of my associative image display kit in the open position;

FIG. 2 is a top plan view thereof;

FIG. 3 is a bottom plan view thereof;

FIG. 4 is an enlarged right side plan view thereof;

FIG. 5 is a left side plan view thereof;

FIG. 6 is a reduced scale front plan view thereof; and,

FIG. 7 is a rear plan view thereof.

In the drawings, the broken lines represent portions of the associative image display kit that form no part of the claimed design.
